UNITED STATES PATENT OFFICE

108,246

DESIGN FOR A RUG

Eula Lee Russum, Washington, D. C.

Application November 22, 1937, Serial No. 73,111

Term of patent 3½ years

To all whom it may concern:

Be it known that I, Eula Lee Russum, a citizen of the United States, residing at Washington, in the District of Columbia, have invented a new, original, and ornamental Design for a Rug, of which the following is a specification, reference being had to the accompanying drawing, forming a part thereof.

The figure of the drawing is a plan view of a rug showing my new design.

I claim:

The ornamental design for a rug, as shown.

EULA LEE RUSSUM.
